H. Hall,
Grinding Mill,
No 18,844, Patented Dec. 15, 1857.

UNITED STATES PATENT OFFICE.

HARVY HALL, OF MANSFIELD, OHIO.

CORN AND COB MILL.

Specification of Letters Patent No. 18,844, dated December 15, 1857.

To all whom it may concern:

Be it known that I, HARVY HALL, of Mansfield, in the county of Richland and State of Ohio, have invented a new and Improved Corn and Cob Mill; and I do hereby declare that the following is a full and exact description thereof, reference being had to the accompanying drawings and to the letters of reference marked thereon.

10 Corn and cob mills, consisting of an internal cone and a corresponding external shell, as heretofore constructed are attended with several defects and difficulties which manufacturers have endeavored in vain to overcome. Uniformity of grinding is and can be attained only by using perfectly parallel surfaces, with a true uniform divergence.

15 It is not difficult, in this kind of mills, to obtain a true circle, parallel surfaces or uniform divergence, but the difficulty is to keep them so. This difficulty arises from the manner of applying the power to the shell, and the manner of resisting it, and vice versa. The effect always is to produce a hard and unsteady draft, meal of unequal fineness, and frequently the loss of the mill by breaking. Of course these effects are not observable when the corn and cobs 20 are in a soft condition, but when the corn becomes dry and the cobs hard and stiff, the resistance is so great that it is impossible, by any invention prior to mine, to keep the cone and shell in proper relative position. On one side the grinding surfaces will be forced in contact, while on the other side they will be forced too wide apart, hence the evils enumerated.

25 Another difficulty is the irregular feeding occasioned by the coarseness of the ears of corn, which not only impede each other's progress in the hopper, but frequently bridge the entire space between the arms of the shell, and then suddenly falling in produce a great strain upon the cob-breakers on that side, and thereby disturb the equilibrium of the draft and the parallelism of the grinding surfaces.

30 The object of my invention is to overcome these difficulties. And after making and trying many forms of mills, I am confident that I have succeeded in constructing a mill that remedies the old evils without being attended by new ones.

35 The difficulties relating to the shell and the cone might be obviated by increasing the

amount of metal to such an extent as to enable them to bear the great pressure without springing, but this involves a great increase of weight and expense.

40 In my mill the object is completely gained in relation to the shell, by making the horse shafts or levers in such a manner as to embrace the shell and render its action equal on all sides, as will be understood by reference to the description below and the drawings.

45 The difficulties relating to the cone are obviated in my mill by casting the meal trough solid to the cone at its base and within three inches of the point of greatest pressure, presenting its broad flat bottom edgewise to the pressure and forming an arch or wheel, receiving the pressure in the direction of rim to center; being strengthened also by the side of the meal trough which is as a flange to the wheel. And it is still further strengthened by the manner of its attachment to the top of the circular pedestal, bringing all its strength (which is 50 equal or superior to the trough and of the same form) to resist the pressure from the shell at all points.

55 The difficulties of feeding are obviated in my mill by an improved cob-cutter, differing wholly from any heretofore known.

60 My invention consists in strengthening the cone without an increase of metal, thus making a better mill at a much less expense by casting the cone and trough in one piece; 65 and also in the combination of a stationary cob-cutter with the cutting edges upon the front of the revolving arms of the shell of the mill, for cutting cobs, regulating the feed diminishing the power required and increasing the rapidity of the grinding.

65 In the accompanying drawings Figure 1, represents the mill as arranged for employing horses, with a part of the hopper B, broken off to show the two sets of cob-breakers n, n, and E, E. Fig. 2, represents the cob-cutter F and the arms D, the latter being broken away from the shell with which they are cast. Fig. 3 shows the cone of the mill and the manner of connecting it with the pedestal. Fig. 4, is a section of the working part of the mill. Figs. 5 and 6 show parts hereafter explained.

70 In operating my mill the shell A, Fig. 1, is turned around, while the cone L, remains stationary, resting firmly upon the pedestal P, and feet Q, which are bolted to a plat-

form. The shell A is cast in the same piece with the arms D, D, which have a series of cob-breakers E, E. The hopper B, is riveted to the shell A, so that both hopper B, 5 and arms D D revolve with the shell. Upon the front of the arms D D is a shear edge, as seen in Fig. 2, at D. As the shell A and arms D, revolve, the shear edges d, pass under a corresponding shear edge upon the 10 stationary arm or cob-cutter F, for the purpose of producing a shear cut which divides the hardest ears of corn with comparative ease. The effect of this shear cut is not only to lessen the power required to drive the 15 mill and prevent the cob-breakers n, and E, from being broken, but the feeding of the mill is more uniform and complete, consequently the mills grind faster.

The cone L, Fig. 3, and the meal trough 20 M, are cast in one piece; so that the meal trough serves the threefold purpose of receiving the meal, of giving a broad base for fastening the cone to the pedestal, and above all, of strengthening the cone without any 25 increase of metal. The bottom of the meal trough M, Fig. 3, has a projection m, which fits into a channel on the upper side of ring P, seen at p, Fig. 3. This channel p, is interrupted near each screw by a projection S 30 Fig. 6, which fits into a corresponding depression in the bottom of the meal trough, seen in perspective at t, Fig. 3, thus forming a lock to prevent too great strain upon the screws r, Fig. 5, which hold the meal trough 35 and ring P, together.

Cone L, Fig. 3, is armed with cob-breakers n, and surrounded by a separate grinding ring o, which is held by screws w. In like manner the shell A, Fig. 4, is armed with 40 cob-breakers E, also with floats or coarse teeth C, and a separate grinding ring G, held by screws. These rings are made of chilled or hard white iron, in order to endure the wear, and being removable they 45 may be replaced by coarse or fine rings or new ones at pleasure.

The cob-cutter F, Fig. 4, is supported by the stationary washer or nut N, which is held to its place by a screw bolt, seen in Fig. 50 4, at x, which passes through the spindle l, to meet a nut z in the cavity of the cone. The nut z when brought home is prevented from turning by fitting a socket in the cavity of the cone, and the washer or nut N is in 55 like manner prevented from turning by fit-

ting upon the square top of the spindle l. The screw bolt turns freely in both the spindle l and the washer N, by means of the lever or wrench y. The object of this screw bolt is not only to hold the parts together 60 but also to regulate the distance between the surface of the cone and that of the shell, in order to produce meal of any degree of fineness.

Around the bottom of the shell A, Fig. 4, 65 is a ring I, which fits the shell and is locked to the latter by a projection seen at a, in dotted lines. This ring has on its under side a series of floats or meal carriers i, which sweep the meal trough M, bringing the meal 70 to the hole v Fig. 5, where the meal falls from the mill. At the under edge of the ring is a flange R, Figs. 4 and 5, projecting downward and embracing the outer lips of the meal trough. In Fig. 1, are shafts W, 75 W, connected by cross-bars Y, Y, and pins f, f, and held firmly in place by bracing rods g, g, which may be tightened at pleasure by means of screws and nuts j, placed at the hooks h, h. The shafts fit upon lugs which 80 are cast with the shell of the mill. By this arrangement the shafts form a completely firm frame which, by acting equally upon both sides of the shell, moves it uniformly 85 upon the cone and prevents any side pressure tending to separate the shell and cone on one side, and bring them in contact on the other.

The advantages of my mill are: 1. The cone is incapable of springing and is held 90 firmly in place. 2. The feeding is more complete and uniform than even when an arm is used instead of the cob-cutter, and the strain upon the cob-breakers being relieved, less power is required to drive the 95 mill. The shafts render the action of the shell equal upon all sides, preventing the irregular wearing of the mill and producing meal of uniform fineness.

Having thus fully described my invention 100 what I claim and desire to secure by Letters Patent of the United States is:

The cone and meal-trough, cast in one piece, for the purpose of strengthening the cone, and giving a firm base for its attachment as set forth.

HARVY HALL.
